[57] CLAIM

The ornamental design for a laptop computer or similar article, as shown and described.

DESCRIPTION

FIG. 1 is a top plan view of a laptop computer or similar article showing my new design with the top being in a closed position;

FIG. 2 is a front elevational view thereof;

FIG. 3 is a right side elevational view thereof;

FIG. 4 is a bottom plan view thereof;

FIG. 5 is a rear elevational view thereof;

FIG. 6 is a left side elevational view thereof;

FIG. 7 is a front elevational view thereof with the top being in an opened position;

FIG. 8 is a right side elevational view thereof;

FIG. 9 is a top plan view thereof; and

FIG. 10 is a top, front, right side perspective view thereof.

The computer is shown in an operative position in FIGS. 7-10.
